UNITED STATES PATENT OFFICE.

BÉLA MAXIMILIAN RAY, OF LONDON, ENGLAND.

ACCESSORY FOR USE IN CONNECTION WITH HAIR WAVING OR CURLING APPLIANCES.

Application filed January 14, 1927, Serial No. 161,139, and in Great Britain December 17, 1926.

This invention relates to an accessory for use in connection with permanent hair-waving or curling appliances. The object of the present invention is to provide a device for use with hair-waving or curling appliances employing steam, for the purpose of isolating a tress of hair to facilitate treatment thereof and at the same time provide means to prevent steam or hot condensate, which escapes or issues from the waving or curling appliance, from reaching the scalp and neighbouring hair, thereby eliminating the unpleasant sensation due to the steam coming into contact with the scalp.

15 Broadly, the invention comprises a shield of rubber or other material impervious to steam and moisture, having an apertured nipple through which the tress is passed prior to being bound round the waver or curler, said shield being adapted to surround and close the lower portion of the waving or curling appliance so as to trap steam or hot condensate escaping or issuing therefrom. The apertured nipple, preferably centrally disposed on the shield, is constructed of rubber or other material of a compressible nature so that the aperture may be closed in steam-tight manner around the hair drawn therethrough. Such closure of the aperture 20 is conveniently effected by binding the compressible nipple close to the lower end of the waver or curler around which the hair is bound, by means of string or the equivalent, but preferably by employing a clip which enables the intensity of pressure upon said nipple to be varied, according to the amount and nature of the hair within the aperture thereof. After treating the hair around the waver or curler in known manner to prevent 25 direct contact of dry hair with steam, the lower barrel or tubular end of a waving or curling appliance is made to enclose the waver or curler with the hair bound therearound. The outer parts of the shield are then gathered round the outside of the lower barrel or tubular end of the waving or curling appliance, being retained in position by a rubber ring or the equivalent, so that steam or hot condensate is trapped in the shield and 30 prevented from reaching the scalp. Auxiliary shields or pads of felt or other suitable material may be employed in addition to the rubber shield so that the rubber shield, when it becomes hot, does not irritate the head.

35 In order that the invention may be more

readily understood, reference is directed to the accompanying sheet of drawings, wherein:

Figure 1 is a pictorial view of the shield constructed in accordance with this invention.

Figure 2 is a sectional view showing the manner of using same; and,

Figures 3 and 4 are pictorial views of two kinds of clips suitable for use in association with the shield, the former kind being adapted to embrace both the nipple and the lower end of the waver or curler, whilst the latter grips the nipple only, being secured to the waver or curler by string or the like; and,

Figure 5 is a fragmentary sectional view of a modified nipple.

Referring to the drawings, the shield 1 of rubber or other suitable material has solutio- 75 nated or otherwise affixed to the centre thereof, a nipple 2 of rubber or other compressible material having an aperture 3 therethrough. If desired, the apertured nipple may be integral with the shield.

In use, a tress of hair 4 is isolated from the remainder of the hair and is passed up through the aperture 3 in the nipple 2, this being conveniently done by looping the end of the tress and drawing it through by means of a hair-pin or other hooked member. The waver or curler 5 is placed adjacent to the nipple 2 and the tress 4 bound around it as illustrated. A steam-tight closure at the aperture 3 is made by compressing or constricting the nipple 2, the simplest manner 80 of effecting this being shown in Figure 2, where a length of string 6 engages with the lower bifurcated end of the waver or curler 5, and is passed round the narrowed neck portion of the nipple 2. Figure 3 shows a 85 convenient form of clip for the same purpose. This clip comprises a band 7 of springy material, the free ends 8, 9 of which are bent or shaped to form finger-pieces. The ends 8, 9 may be drawn together so as 90 to adjust the bore of the clip and so intensify the pressure on the enclosed nipple 2. Adjustment is effected by a hooked member 10 hingedly mounted on the end 8 and adapted to engage with one pair of a series of 95 teeth or spaced projections 11 on the end 9. An alternative form of clip is illustrated in Figure 4, wherein a length of wire is bent to substantially V-shape, being provided with 100 a looped end 12 which tends to keep the 105

110

limbs 13, 14 wide apart. A ring 15 is threaded on the hooked outer end of the limb 13 and is adapted to swing round and retain the limb 14 in close proximity to the limb 13, between which limbs the apertured nipple 2 with the tress passing therethrough is gripped. The clip is secured to the lower end of the waver or curler 5 by string or the equivalent. To avoid direct contact of the steam with the dry hair, the hair is saturated with any suitable liquid or a protective wrapping 16 of "sachet", lint, blotting paper, oil-proof paper or the like is applied. The protected hair 4 and the waver or curler 5 is housed within the lower barrel or tubular end of the waving or curling appliance 17, around the outside of which the shield 1 is gathered and there retained by a rubber ring 18 or the equivalent. A cup-like casing is thus formed in which any steam or hot condensate escaping or issuing from the waving or curling appliance is trapped.

A modified form of nipple is shown in Figure 5, where, instead of shaping the nipple to form a necked portion as in Figure 1, a tubular portion 19 of even thickness is doubled back upon itself, giving in effect a thickened wall.

An auxiliary washer or shield or pad of felt or the like—not shown in the drawings—may be positioned on the head below the rubber shield hereinbefore referred to. Such auxiliary washer is preferably constructed so that it may be slipped on the head sideways to avoid threading the hair therethrough. To this end a radial slit is made from the central aperture in the washer to the outer edge thereof so that a gap may be formed by temporarily parting the material of either side of the slit to allow the tress of

hair to slip sideways into the central aperture in the said felt washer.

I claim:

1. An accessory for use in connection with hair-waving and curling appliances comprising a flexible body portion having a central nipple portion for receiving a tress of hair, means for compressing said nipple about the tress of hair, said flexible body portion being adapted to surround and completely encase the end of a curling or waving appliance for the tress of hair and means for holding said flexible body portion about the end of the appliance. 45

2. An accessory for use in connection with hair-waving and curling appliances comprising a body of flexible material, a nipple carried by the body and providing means for receiving a tress of hair to be curled, the portion of the body between the edge thereof and the nipple constituting a flexible appliance enveloping skirt, and means for holding the edges of said skirt about the appliance. 50

3. An accessory for use in connection with hair-waving and curling appliances comprising a body of flexible material, a nipple carried by the body and also being of flexible material, means for compressing the nipple, an appliance enveloping skirt formed by the body between the nipple and the periphery thereof, and said skirt portion constituting an enveloping shield for the end of an appliance for curling or waving the hair and means for holding the skirt portion clustered about the appliance. 65 70 75

In testimony whereof I have affixed my signature hereto this 30th day of December, 1926.

BÉLA MAXIMILIAN RAY.
